UNITED STATES PATENT OFFICE

2,138,008

AMUSEMENT DEVICE

Adrian S. Jones, Redwood City, Calif.

Application December 28, 1936, Serial No. 117,692

5 Claims. (Cl. 104—164)

The present invention relates to improvements in amusement devices, and has reference to a railroad and roadway system having means associated therewith for selectively regulating traffic passing thereover. The apparatus is constructed in such a manner that youngsters will not only be afforded amusement in operating the trains and other traffic, but will also derive a certain amount of instruction from the operation there-
10 of.

It is particularly proposed to provide a railroad track and a roadway crossing the track. I employ a novel system of signals for controlling movement of the trains traveling on the track
15 and for regulating the traffic passing along the roadway.

As a further object of the invention I propose to provide a roadway for traffic having a runway arranged to form part thereof, and made to be
20 tilted into an inclined position for imparting movement to the traffic. I also utilize a barrier that normally is disposed on the level of the roadway, and which may be raised by the operator for halting the traffic on the roadway.

25 With these and other objects in view, my invention consists in the combinations, constructions and arrangement of parts, hereinafter described and claimed.

For a better understanding of my invention,
30 reference should be had to the accompanying drawings, forming part of this application, in which:

Figure 1 is a plan view of my amusement device;

35 Figure 2 a transverse vertical sectional view taken along line 2—2 of Figure 1;

Figure 3 a sectional view on line 3—3 of Figure 2;

Figure 4 a transverse sectional view taken
40 along line 4—4 of Figure 1;

Figure 5 a vertical section along line 5—5 of Figure 4 with the runways in tilted position;

Figure 6 a sectional view along line 6—6 of Figure 1, the barrier being elevated above the
45 roadway; and

Figure 7 an enlarged view of the right-hand portion of Figure 5.

While I have shown only the preferred form of my invention, it should be clearly understood
50 that various changes or modifications may be made within the scope of the appended claims without departing from the spirit of the invention.

In carrying out my invention I provide a frame
55 generally indicated at 1, and comprising in its

structural features a top 2 having legs 3 for supporting the top at a convenient height above a floor or the like.

It will be noted from Figure 1 that I mount an endless track 4 on the upper surface of the top 2, and an electric train 5 is adapted to travel along the track. The construction of the train is conventional, and a reversible rheostat is provided as at 6 for regulating the speed and direction of travel of the train. I have shown
10 a tunnel at 7 which houses part of the track.

For controlling the movement of the train I provide a signal 8, which consists of a sheet of material 9 secured to the upper end of a vertical shaft 10. The sheet is formed with an aperture 11 having an electric light 12 mounted therein. I have shown the signal as being arranged in substantially parallel relation with the side section 14 of the track, and a shaft 15 is connected to the shaft 10 through segmental
15 bevel gears 16, (see Figure 3).

The signal 8 may be turned from the position shown in Figure 1 into transverse relation with respect to the track 4. During this movement a contact arm 17 secured to the shaft 15 and insulated therefrom will strike a contact 18 and close an electric circuit 19 so as to illuminate the light 12. The light is observable from either side of the sheet 9 and, if desired, the latter may have reflector buttons 19 mounted thereon
20 to enhance the appearance of the signal.

I provide a roadway indicated generally at 20, which is arranged to cross the track 4 in the manner shown in Figure 1. A base 21 of rectangular outline is mounted on the top 2, and partitions 22 rise therefrom in parallel relation with respect to each other to define stationary road sections 23 and 24. Runways 25 and 26 are aligned with the section 23, while runways 27 and 28 are arranged in alignment with the section 24.

It will be noted that each of the runways 25 to 28, inclusive, has a wall 29 extending along three sides thereof, the open ends 30 of the runways being arranged to face the stationary road sections 23 and 24 so as to allow traffic, such as an automobile 31, (see Figure 7), to pass from the runway on one side of the track 4 to the aligned runway on the other side of the track.

For imparting movement to the traffic I provide means for hinging the ends 30 of the runways to the top 2 as at 32, whereby the runways may be tilted into an inclined position for moving the traffic from one runway to the aligned runway on the opposite side of the railroad track. I
50 55

have shown the hinging means as consisting of bolts 33 fixed to the runways and projecting downwardly through openings 34 in the top 2, (see Figure 7). Springs 35 are arranged to urge 5 the runways upon the top 2.

For tilting the runways, I make use of rods 36, having offset portions 37 disposed beneath the runways, and these rods have crank handles 38 at the outer ends thereof. The rods are rotatably 10 supported, and upon turning handles 38, the runways are tilted into angular position for imparting movement to the traffic.

Referring now to Figures 1 and 7, it will be noted that I provide a recess 39 extending transversely across the roadway 20, and a barrier 40 normally forms a closure over the recess to allow 15 passage of traffic thereover.

In Figure 6 I have shown the barrier as being raised above the level of the roadway for halting 20 traffic, while in Figure 7 the top rail 41 of the barrier is arranged flush with the roadway and forms part of the latter. Strips 42 are hinged to the top rail at 43 and to the bottom of the recess at 44.

For raising and lowering the barrier, I make 25 use of an eccentrically mounted disc 45 that is connected to one of the strips 42 by means of a link 46. A crank 47, (see Figure 1), is operated by a hand-wheel 48, and upon actuating the latter the barrier may be raised or lowered.

As a further warning to the traffic I mount 30 electric lights 49 on the barrier, and a switch 50 closes an electric circuit 51, which includes the lights 49, when the barrier is in raised position 35 above the roadway.

The traffic along the roadway is controlled by 35 regulating signals 52, which are normally disposed below the roadway in the manner shown in Figures 4 and 5. Each signal comprises a sheet of material 53 having lights 54 mounted in an 40 apertured portion 55 of the sheet, the lights being visible from either side of the signals when the latter are raised above the roadway.

Rods 56 extend downwardly from the signals, 45 and the lower ends of the rods are interconnected by cross members 57. A lever 58 is swingably mounted at 59, (see Figure 4), and the free end 60 thereof is engageable beneath a stop 61 for the purpose of holding the signals in lowered position. Springs 62 are provided for urging the 50 signals upwardly through slots 63 when the lever 58 is released.

As the signals are moved upwardly, a switch 64 is closed and the lights 54 are illuminated, the 55 wiring circuit being shown in Figure 5. It should be noted that the signals 52 are mounted on opposite sides of the track 4 so as to be visible to traffic coming from either direction.

From the foregoing description of the various 60 parts of the apparatus, the operation thereof may be readily understood. The electric train is set in motion, and the speed and direction thereof is regulated by means of the rheostat 6. Warnings are given to the operator of the train by the signal 6 in the manner previously set forth.

The traffic is moved over the roadway by inclining the selected runway, and the traffic may 65 be controlled by the regulating signals 52. In the event that the operator should desire to stop all traffic on the roadway, the barrier 40 is raised 70 above the level of the road.

I claim:

1. In an amusement device, a table, a road section thereon, two movable runways arranged on opposite ends of the road section and with their inner ends in abutting relation thereto, spring 5 means engaging each runway near its abutting end for holding the latter to the table and in abutting relation to the road section and for yieldably opposing raising of its outer end, and transverse rods carried by the table having 10 cranks underneath the outer ends of the runways and having handles along the edge of the table whereby the two runways may be independently raised and lowered in rapid play to desired angularities for causing a vehicle to run 15 back and forth between the extremities of the runways and over the road section in immediate response to control movements of an operator.

2. In an amusement device, a road section, two movable runways arranged on opposite ends of 20 the road section and with their inner ends in abutting relation thereto and quick-acting means for independently tilting each of the runways whereby they may be independently raised and lowered in rapid play to desired angularities for 25 causing a vehicle to run back and forth between the extremities of the runways and over the road section in immediate response to control movements of an operator.

3. In an amusement device, a road section, 30 means for periodically passing traffic transversely thereacross, two runways tiltably disposed on opposite ends of the road section and means for independently tilting the runways to permit an operator to propel a vehicle from runway to runway over the road section in timed relation to the movement of the traffic passing across the road section.

4. In an amusement device, a road section, means for periodically passing traffic transversely thereacross, a runway tiltably disposed in alignment with the road section and means for 40 tilting the runway up and down to permit an operator to propel a vehicle from the runway over the road section in timed relation to the movement of the traffic passing across the road section.

5. In an amusement device, a table, a road section thereon, two movable runways arranged on opposite ends of the road section and with 50 their inner ends in abutting relation thereto, spring means engaging each runway near its and having handles along the edge of the table and in abutting relation to the road section and for yieldably opposing raising of its outer end, 55 and transverse rods carried by the table having cranks underneath the outer ends of the runways and having handles along the edge of the table whereby the two runways may be independently raised and lowered in rapid play to desired angularities for causing a vehicle to run back and forth between the extremities of the runways and over the road section in immediate response to control movements of an operator, the handles 60 being sufficiently close together to allow both handles to be grasped simultaneously by the operator.

CERTIFICATE OF CORRECTION.

Patent No. 2,138,008.

November 29, 1938.

ADRIAN S. JONES.

It is hereby certified that error appears in the printed specification of the above numbered patent requiring correction as follows: Page 2, second column, line 53, claim 5, strike out the words "and having handles along the edge of the table" and insert instead abutting end for holding the latter to the table; and that the said Letters Patent should be read with this correction therein that the same may conform to the record of the case in the Patent Office.

Signed and sealed this 10th day of January, A. D. 1939.

Henry Van Arsdale
